CONTROL APPARATUS.

Application filed August 7, 1926. Serial No. 127,728.

This invention relates to control apparatus and particularly to locking attachments primarily designed for use in conjunction with overload relays.

5 The object of the invention, generally stated, is the provision of locking attachments for overload relays that shall be simple and efficient in operation and capable of being readily and economically manufactured.

10 A more specific object of the invention is to provide for limiting the number of times a relay may be operated without being manually reset by an operator.

15 Another object of the invention is to facilitate the setting of the relay to operate any predetermined number of times.

It is also an object of the invention to provide means for indicating the number 20 of times a relay has been operated.

Other objects of the invention will, in part, be obvious and, in part, appear hereinafter.

25 This invention is disclosed in the embodiment thereof shown in the accompanying drawing and comprises the structural features and the combination of elements and arrangement of parts which will be exemplified in the construction hereinafter set forth, and the scope of the application of which will be indicated in the claims.

30 For a fuller understanding of the invention, reference may be had to the following detailed description, taken in connection with the accompanying drawing in which;

35 Fig. 1 is a view, in front elevation, of a relay provided with a locking attachment constructed in accordance with this invention;

40 Fig. 2 is a view, in side elevation, of the locking attachment;

45 Fig. 3 is a diagram of connections showing how the relay and locking attachment may be connected in a circuit.

50 Referring now to the drawing, the reference character 10 designates, generally, an overload relay, of any well-known type, mounted on a panel 11. In this particular construction, the overload relay comprises a coil 12 that is disposed on the panel 11 directly above a pivotally mounted armature 13.

As shown, the armature 13 is pivotally mounted at 13' and is disposed in alinement

55 with a switch-actuating rod 14 which extends through the magnet coil 12. In order to set the armature 13 relative to the coil 12, a set screw 15 is adjustably mounted in a lug 16 that is provided on the relay frame. The set screw is disposed to engage a 60 pending arm 17 on the armature 13.

The relay magnet coil 12 may be connected in its circuit by means of terminal members, such as shown at 18. Since relays of this type are used for motor circuits 65 and the like, the magnet coil 12 is designed to carry heavy currents without excessive heating.

70 In order to utilize the relay for interrupting circuits, upon the flow of excessive currents, it is provided with switch members or disks, such as 19 and 20, which may be connected in a line-switch-coil circuit. In this embodiment of the invention, in order to simplify the construction, the switch members 19 and 20 are mounted on the rod 14 and insulated therefrom in any suitable manner.

75 The switch member 19 is disposed to seat on contact members 21 and 22, while the switch member 20 is positioned to engage the contact members 23 and 24. These contact members are provided for connecting the switch members in the line-switch-actuating circuits. As illustrated, the contact members may be mounted on the panel 11 by means of a plurality of bolts 25, which may also serve as terminals for engaging the circuit conductors.

80 As shown, springs 26 are positioned on the rod 14 for retaining the switch members 19 and 20 in position. It will be readily understood that the upper spring 26 may be limited in its upward movement in any suitable manner, such as by providing an extension 27 on the relay frame that extends toward the rod 14. The provision of springs permits a certain movement of the switch members 19 and 20, and assures the desired 85 good contact between the switch members and the contact members.

90 When it is desired to retain the switch members 19 and 20 out of engagement with the contact members 21 to 24, inclusive, for a predetermined period after the relay has 95 functioned upon the flow of an excessive current, provision is made for locking the switch members in their open positions. In 100 105

this construction, the locking is effected by a latch 28 which retains the armature 13 in its raised position.

As illustrated, the latch 28, which also 5 functions as an armature, is pivotally mounted at 29 and is so disposed that, when it hangs in its normal position, it will prevent the armature 13 from dropping to its lower position after it has been actuated 10 by the magnet coil 12.

In order to operate the latch 28 to release the armature 13, a coil 30 is provided. The coil 30 may be energized from any suitable source and, as will be described hereinafter, 15 its circuit may be controlled by any suitable manually operable switch.

When overload relays of this type are utilized on street cars and the like with a view to protecting the apparatus, it is sometimes 20 desirable to limit the number of times that they may be reset by an operator. The provision of means for limiting the number of times that an overload relay may be set, and the locating of the device in a more 25 or less inaccessible position, suggests to the operator an inspection of the other apparatus on the vehicle before he opens the relay box to reset the relay manually.

The relay attachment provided in this 30 particular case comprises a switch member 31 that is disposed to engage contact members 32 mounted on the relay panel. The purpose of these contact members will be described hereinafter. As illustrated, the 35 switch member 31 is carried by an arm 33, which is pivotally mounted at 34 on an extension 35 of the relay frame.

In order to actuate the switch member 31, 40 a cam 36, that is carried by a shaft 37, is disposed in alignment with the arm 33. As shown, the shaft 37 is rotatably mounted in bearings 38 that are formed on the extension 35 of the relay frame.

The actuation of the cam 36 may be effected in any suitable manner and, in this 45 particular construction, means are interposed between the switch actuating rod 14 and the shaft 37 for utilizing the reciprocating motion of the rod 14 for rotating the shaft 37. This shaft-rotating means comprises a crank arm 39, which is loosely mounted on the shaft 37 and is pivotally connected by means of a pin 40 to the rod 14. In order to permit the rod 14 to move 50 freely, slots are provided in the crank arm 39 in order that the pin 40 may move longitudinally thereof during the reciprocating movement of the rod 14. A spring pawl 41 is carried by the crank arm 39 and is disposed to engage the teeth of a ratchet wheel 42, which is fixed to the shaft 37 by means 55 of a set screw 43.

As illustrated, a knurled hand-piece 44 is mounted on the end of the shaft 37, so that 60 the latter may be actuated manually. Thus

the cam 36 may be set by the operator in any desired position relative to the arm 33.

As will be observed, the switch member 31 70 may be retained in engagement with the contact members 32 by setting the raised or projecting portion 45 of the cam 36 to engage the arm 33. Further, the arm 33 is retained continually in engagement with the cam 36 by means of a spring 46, which is interposed between the lower end of the arm 33 and a 75 projection 47 that is provided on the relay frame.

It will be readily understood that the 80 number of times the relay may be reset by means of the coil 30 will depend on the relation that the distance between the teeth of the ratchet wheel 42 bears to the arc of a circle through which the raised portion 45 of the cam extends.

In order to facilitate the setting of the cam 85 to permit the relay to be reset any predetermined number of times, a graduated disc 48 is pinned to the shaft 37 and is provided with a plurality of teeth 49, which are shaped to intermesh with teeth 50 formed on the inner face of the cam 36. As illustrated, the cam is retained in position on the shaft 37 by a nut 51, which serves to force the teeth 50 into engagement with the teeth 49 on disc 48.

The cam is also provided with graduation 90 marks, best shown in Fig. 2. Thus, when the cam is set relative to a selected graduation mark on the disc 49, and the zero on the disc is set to coincide with a mark on the bearing 38, the relay may be reset a predetermined number of times and the number 95 will be indicated by the disc 48.

In order that the functioning of the relay and the attachment may be more clearly 100 understood, its operation when connected in a simple circuit, such as shown in Fig. 3, will now be described. In the circuit diagram illustrated, the relay coil 12 is connected in series relation with a driving motor 52 by means of a conductor 53.

In order to interrupt the motor circuit in case of an overload caused, for instance, 105 by a short-circuit, two circuit-breakers or line switches 54 and 55 are connected in the conductor 53. These circuit-breakers are normally retained open by springs 56 and may be actuated to their closed positions by coils 57 and 58, respectively.

The coils 57 and 58 may be energized from 110 any suitable source of current supply and, in this particular circuit, they are disposed to be connected to the trolley line 60 upon the actuation of an auxiliary drum 61, which may be operated in conjunction with the 115 customarily provided master controller. The circuits established for effecting the energization of the coils 57 and 58 extend through conductor 62 leading from the trolley-pole 120 63 to a contact segment 64 of the drum 61, 125

and then through conductors 65 and 66 to the coils 57 and 58, respectively, to ground at 74. The relay switch members 19 and 20 are connected in the conductors 65 and 66.

8 The relay coil 30 may be energized from any suitable source of electrical energy and, in this particular circuit, a storage battery 59 is provided.

9 As will be observed, the conductor 69, extending between the battery and the coil 30, has a gap 70 therein which may be bridged by a contact segment 67 carried by the auxiliary drum 61, in its "off" position. Consequently, the circuit of the coil 30 cannot be 15 closed unless the drum 61 is in its "off" position when the contact segment 67 will bridge gap 70.

10 As shown, a manually operable switch 68 is connected in the conductor 69 to provide 20 means for the manual control of the energization of the coil 30. Therefore, when the drum 61 is in its "off" position, by closing the switch 68, a circuit may be established from the battery 59, through contact 25 segment 67 bridging gap 70, conductor 69, switch 68, resistance unit 71, coil 30, conductor 72, and contact members 32, which are bridged by switch member 31, to ground at 73.

30 Assume that the circuit-breakers 54 and 55 have been closed through the operation of the drum 61 and that the motor 52 is in operation. If a short-circuit occurs, so that an excessive current flows in the motor circuit,

35 the coil 12 functions to actuate the armature 13, which swings upward and strikes the switch-actuating rod 14. The switch members 19 and 20 are raised, and the circuits through the actuating coils 57 and 58 are thus opened. Accordingly, the 40 line switches or circuit-breakers 54 and 55 are dropped out, and the motor circuit is broken.

When the armature 13 swings upward, it 45 is locked in its raised position by the latch 28. In this manner, the switch members 19 and 20 are retained in their raised positions so that the motor circuit cannot be closed until the armature 13 is released.

50 In order to close the circuit provided for energizing the coil 30, the auxiliary control drum 61 is first thrown to its off position to cause the contact segment 67 to bridge the gap 70; then, upon the closure of the switch 55 68, current flows in the circuit of the coil 30, which has already been traced, and the latch 28 is actuated to release the armature 13. The switch members 19 and 20 are then moved to closed positions, by reason of their 60 own weight.

Each time the switch-actuating rod 14 is raised, the spring pawl 41 carries the ratchet-wheel 42 one step forward, thereby rotating the cam 36. When the rod 14 drops to 65 its lower position, the pawl 41 is drawn

backward over the ratchet wheel 42 to engage the next tooth. In this manner, the cam 36 is advanced step-by-step, as the switch members 19 and 20 are actuated.

When the cam 36 has been turned through 70 a predetermined angle, the arm 33 drops off the raised portion 45 of the cam, and the spring 46 functions to rotate the arm 33 counter-clockwise, as viewed in Fig. 2, thereby actuating the switch member 31 and 75 opening the circuit through which the coil 30 is energized. Therefore, after the switch members 19 and 20 have been actuated a predetermined number of times, causing the cam 36 to rotate through a predetermined 80 angle, the latch 28 cannot be again actuated until the cam has been reset manually to move the switch member 31 into engagement with the contact members 32.

It will be readily understood that, by removing the nut 51, the cam 36 may be set in any desired position relative to the disc 48. In this manner, provision may be made for interrupting the reset circuit after any predetermined number of operations of the switch members 19 and 20 by the relay, for the purpose previously set forth.

While the illustrated example constitutes a particular embodiment of my invention, I do not limit myself strictly to the details 95 herein shown, since, manifestly, the same may be considerably varied without departing from the spirit of the invention as defined in the appended claims.

I claim as my invention:

1. The combination with a relay provided with a switch, of means for locking the switch in a predetermined position, means for releasing the switch, and means positively actuated by the switch for rendering 105 the releasing means inoperative.

2. The combination with a relay, of a switch, actuating means for the switch, means for locking the switch against operation, means for releasing the switch, and 110 means disposed for operation by the switch-actuating means to render the releasing means inoperative.

3. The combination with a relay, of a switch member disposed for actuation by the 115 relay, means for locking the switch in a predetermined position, means for releasing the switch, and means positively actuated by the switch, for rendering the releasing means inoperative after a predetermined number 120 of operations.

4. The combination with a relay, of a switch member disposed for actuation by the relay, means for locking the switch member in a predetermined position, means for releasing the switch member, cam-actuated means for rendering the releasing means inoperative, and means operated by the switch member for operating the cam.

5. The combination with a relay, of a 130

switch member disposed for operation by the relay, means for locking the switch member, means for releasing the switch member, a second switch for rendering the releasing means inoperative, a cam for actuating said second switch, and means operated in conjunction with the switch member for actuating the cam.

6. The combination with a relay, of a switch member disposed for operation by the relay, means for locking the switch member in a predetermined position, means for releasing the switch member, a switch for rendering the releasing means inoperative, a cam for actuating the switch, and a pawl-and-ratchet mechanism for rotating the cam adapted to be actuated by the switch member, whereby the cam is advanced step-by-step as the relay functions.
7. The combination with a relay, of a switch member disposed for operation by the relay, means for locking the switch member against operation, means for releasing the switch member, a second switch for rendering the releasing means inoperative, a cam for actuating said second switch, a

pawl-and-ratchet mechanism for rotating the cam adapted to be actuated by the switch member, whereby the cam is advanced step-by-step through the operations of the relay, and means for setting the cam in different positions relative to the pawl-and-ratchet mechanism.

8. The combination with a relay, of a switch member disposed for operation by the relay, means for locking the switch member against operation, means for releasing the switch member, a second switch for rendering the releasing means inoperative, a cam for actuating said second switch, a pawl-and-ratchet mechanism for rotating the cam adapted to be actuated by the switch member, whereby the cam is advanced step-by-step through the operations of the relay, means for setting the cam in different positions relative to the pawl-and-ratchet mechanism, and means for indicating the number of times the relay operates.

In testimony whereof, I have hereunto subscribed my name this 5th day of August, 1926.

WILLIAM G. HORN.
